UNITED STATES PATENT OFFICE.

JOHN KOHKE, OF ATLANTA, GEORGIA, ASSIGNOR TO AMERICAN CAN COMPANY, OF NEW YORK, N. Y., A CORPORATION OF NEW JERSEY.

MACHINE FOR MANUFACTURING ONE-PIECE FOLDED SHEET-METAL TURPENTINE-CUPS.

No. 900,394.

Specification of Letters Patent.

Patented Oct. 6, 1908.

Application filed May 8, 1908. Serial No. 431,666.

To all whom it may concern:

Be it known that I, JOHN KOHKE, a citizen of the United States, residing in Atlanta, in the county of Fulton and State of Georgia, 5 have invented a new and useful Improvement in Machines for Manufacturing One-Piece Folded Sheet-Metal Turpentine-Cups, of which the following is a specification.

My invention relates to improvements in 10 machines for manufacturing long, narrow, deep, one-piece folded sheet metal turpentine cups, having substantially upright or slightly flaring sides and widely flaring ends and integral angle folds at the flaring ends.

15 My invention is a machine for folding the integral angle folds or wings at the corners of the cup or receptacle against the flaring ends thereof, one pair of such wings or angle folds overlapping the other, and it comprises in 20 coöperative combination a horn mounted upon a movable slide and conforming to the interior of the sheet metal cup, a lower stationary wing folding die and an upper reciprocating wing folding die mounted upon a 25 reciprocating slide independent of the horn slide, each of said wing folding dies being furnished with inclined or flaring die members.

It further consists in the novel construction of parts and devices and in the novel combinations of parts and devices herein shown and described.

In the accompanying drawing, forming a part of this specification, Figure 1 is a front 30 elevation of a machine embodying my invention; Fig. 2 is a cross section on line 2—2 of Fig. 1; Fig. 3 is a horizontal cross section on line 3—3 of Fig. 1; Fig. 4 is a vertical cross section on line 4—4 of Fig. 1; Fig. 5 is a bottom view of the upper folding die; Fig. 6 is a top of the formed sheet metal blank before the wings or angle folds are folded down against the flaring ends of the receptacle by my machine, and Fig. 7 is an end view of the 40 formed blank after it has been operated upon by my machine.

In the drawing A represents the frame of the machine, B the vertically movable interior horn, B¹ the reciprocating slide to 50 which it is secured.

C is the driving shaft.

D is the lower wing folding die and D¹ the upper reciprocating wing folding die.

The horn B has slightly flaring side faces

b¹ b¹ and a bottom face b² corresponding to the sides x and flaring ends x¹ and bottom x² of the formed sheet metal blank X. The horn B is preferably integrally secured to its reciprocating slide B¹. The horn slide B¹ is automatically restored to position by a spring B² surrounding the ejector pin or stem B³ which is secured to the slide B¹ and operates to eject the folded blank X¹ from the lower sliding die D. The lower sliding die D is removably secured to the frame A by bolts d, and it is furnished with integral inclined or flaring die members d¹ d¹ adapted to engage the angle folds or wings x³ of the formed blank X, and by coöperation with the flaring end faces b¹ 60 of the horn B, folds said wings or angle folds x³ upward against the flaring ends x¹ of the blank X when the horn B is reciprocated or pushed down by the upper wing folding die D¹.

75 The upper wing folding die D¹ is removably secured by bolts d¹² to the reciprocating slide D², and it is furnished with a similar inclined or flaring die members d¹¹ similar to those on the lower die D. The folding die slide D² is 80 reciprocated as required, preferably by a crank C¹ on the driving shaft C through the connecting rod or pitman C². The folding die or slide D² reciprocates in suitable guides or ways D³ on the frame of the machine. 85 And the horn slide B¹ likewise reciprocates in suitable guides or ways D⁴ on the frame of the lower die D.

In operation the former blank X is placed 90 on the horn B and then the crank C¹ through the slide D³ pushes down the upper wing folding die D¹, thus causing the upper pair of wings x² on the blank X to be partially folded down against the flaring ends x¹ of the blank X, the spring B² causing the horn B to 95 offer sufficient resistance to the upper wing folding die D¹ to accomplish this preliminary folding of the upper pair of wings x², so that the upper pair of wings x² will fall within the lower pair of such wings, and then the 100 further downward movement of the slide D³ carries with it the horn slide B¹ and thus causes the horn B by its coöperation with the lower wing folding die D to fold the lower pair of wings x³ upward and to overlap the 105 upper pair of wings x², and then, as the upper folding die D¹ completes its downward movement, the two pair of wings on the blank X

are completely folded against the flaring ends, as illustrated in Fig. 7. As the upper folding die D¹ withdraws or returns to position the spring B² restores the horn and horn slide to position and causes the upper end of the ejector stem B³ or the lug on the horn slide to which it is secured to lift or free the folded cup from the lower folding die D.

I claim:

- 10 1. In a machine for folding the wings or angle folds of a one-piece-formed sheet metal blank against the flaring ends thereof, the combination with a horn having flaring end faces mounted upon a reciprocating slide, of a lower stationary wing folding die having inclined or flaring die members, and an upper reciprocating wing folding die having inclined or flaring die members, substantially as specified.
- 15 2. In a machine for folding the wings or angle folds of a one-piece-formed sheet metal blank against the flaring ends thereof, the combination with a horn having flaring end faces mounted upon a reciprocating slide, of a lower stationary wing folding die having inclined or flaring die members, and an upper reciprocating wing folding die having inclined or flaring die members, a spring acting against the said horn slide to cause the movable folding die to fold one pair of angle folds or wings in advance of the other pair so that the final pair will overlap the first pair, substantially as specified.
- 20 3. In a machine for folding the wings or angle folds of a one-piece-formed sheet metal blank against the flaring ends thereof, the combination with a horn having flaring end faces mounted upon a reciprocating slide, of a lower stationary wing folding die having inclined or flaring die members, and an upper reciprocating wing folding die having inclined or flaring die members, a spring acting against the said horn slide to cause the movable folding die to fold one pair of angle folds or wings in advance of the other pair so that the final pair will overlap the first pair, substantially as specified.
- 25 4. In a machine for closing or folding the wings or angle folds of a one piece folded sheet metal vessel against the flaring ends thereof, the combination with a horn having flaring die faces, of wing folding dies on opposite sides of the horn and having inclined or flaring die members and means for causing said wing folding dies to successively act against the horn, substantially as specified.
- 30 5. In a machine for closing or folding the wings or angle folds of a one piece folded sheet metal vessel against the flaring ends thereof, the combination with a horn having flaring die faces, of wing folding dies on opposite sides of the horn and having inclined or flaring die members and means for causing said wing folding dies to successively act against the horn, substantially as specified.

blank against the flaring ends thereof, the combination with a horn having flaring end faces mounted upon a reciprocating slide, of a lower stationary wing folding die having inclined or flaring die members, and an upper reciprocating wing folding die having inclined or flaring die members, a spring acting against the said horn slide to cause the movable folding die to fold one pair of angle folds or wings in advance of the other pair so that the final pair will overlap the first pair, and means for freeing the formed and folded blank from the horn folding die, substantially as specified.

4. The combination with a movable horn having flaring end faces, of a stationary wing folding die and a reciprocating wing folding die acting to move the horn in co-operation with the stationary wing folding die after starting the folding of the pair of wings engaged by said wing folding die, substantially as specified.

5. In a machine for closing or folding the wings or angle folds of a one piece folded sheet metal vessel against the flaring ends thereof, the combination with a horn having flaring die faces, of wing folding dies on opposite sides of the horn and having inclined or flaring die members and means for causing said wing folding dies to successively act against the horn, substantially as specified.
